C. F. Bond

his ATTORNEY.

UNITED STATES PATENT OFFICE.

HORATIO GATES HOUGHTON, OF GREEN BAY, WISCONSIN.

HUMIDIFIER.

1,233,474.

Specification of Letters Patent. Patented July 17, 1917.

Application filed August 3, 1916. Serial No. 112,961.

To all whom it may concern:

Be it known that I, HORATIO G. HOUGHTON, a citizen of the United States of America, residing at Green Bay, in the county of Brown and State of Wisconsin, have invented certain new and useful Improvements in Humidifiers, of which the following is a specification, reference being had therein to the accompanying drawing.

10 The invention relates to a humidifier, preferably, though not exclusively, in apartment, office or other buildings, where heating radiators are used, to maintain the humidity of the air at a certain temperature. 15 To render rooms or quarters heated by radiators comfortable, care is taken that a sufficient amount of aqueous vapor permeates the air, as otherwise individuals living there become afflicted with diseases whose origin 20 may be directly traced to the absence of humidity. At a temperature of 72 degrees it has been found that the humidity in the average dwelling is only 28 per cent., and this accounts for the number of diseases of the 25 mucous membranes, such as catarrh, colds, and the like, and is the cause of the cracking of furniture.

It therefore constitutes the principal object of the invention to provide a device 30 which, used in connection with a heating radiator or with any other heating apparatus, supplies the air with moisture to maintain sufficient relative humidity to eliminate the fatal results caused by low humidity. 35 It is a subsidiary feature of the invention to provide a humidifier which may be applied to any radiator and may be quickly and conveniently rearranged where the spacing of the radiator columns or coils differs 40 from standard dimensions.

A further object relates to the construction of the device to permit its being folded or collapsed so as to occupy a minimum of space and to form a compact arrangement.

45 A further object of the invention embraces the provision of means for indicating the level of the water contained in the device.

It is also an object of the invention to provide certain details and features of construction and combinations tending to enhance the effectiveness and general desirability of a device of this particular character.

50 With these and other objects in view the preferred embodiment of the invention consists in the novel arrangement and combination of parts hereinafter described and spe-

cifically pointed out in the appended claims, reference being had to the accompanying drawing, in which—

Figure 1 is a perspective view of the device made in accordance with the invention;

Fig. 2 is a side view of the device in folded position;

Fig. 3 is a fragmentary view of the vertical plate of the device having indicating means arranged thereon;

Fig. 4 is an enlarged perspective view of a wick holder and a portion of the wick;

Fig. 5 indicates a transverse section of the device shown in connection with the radiator.

Referring to the drawing, 1 designates a receptacle in the form of a shallow pan which may be placed underneath a heating radiator or other heating apparatus for a purpose hereinafter to be described. A plate 2 is connected with the side wall of the receptacle by means of hinges 3, 3, whereby it may be placed vertically in a position for service or may be arranged horizontally in a position for storage, as indicated in Fig. 2. In the latter position the plate 2 forms a cover for the receptacle 1, which may be thus conveniently stored away or shipped, by reason of its compact arrangement. The cover 2 is formed integral with side flanges 4, which taper from the rear to the front, and terminates at the front edge in a bead 5 which is adapted to overhang the edge of the adjacent receptacle 90 wall. To lock the plate 2 in vertical position a piece 6 is pivotally secured at the inside of the pan 1 to its rear wall by a pin or rivet 7, and is adapted to be swung upwardly so as to engage the plate 2 and hold the same in vertical position. To release the plate 2 preparatory to closing the device the member 6 is rotated about 180 degrees, so as to lie wholly within the pan 1, whereupon the plate may be lowered into closed position.

Near the upper or outer edge of the plate 2 a bar 8 is provided at a suitable distance therefrom, and its ends are offset and secured to the plate 2 in any approved or suitable manner, such as by rivets. On the bar a plurality of wick holders are arranged, each of which comprises a clip 9 adapted to be shifted on the bar 8. The wick holder proper is formed by two spring plates 10 which have their ends bent at right angles thereto for the purpose of fastening to said

clip. The forward ends of the spring plates 10 are bent away from each other to facilitate the insertion of a wick 11. Near one end the bar 8 is provided with a cut-away portion 12, to permit the ready mounting of the clips 9 on the bar 8, as will be readily understood.

In the application of the device the cover or plate 2 is locked in upright position. The 10 pan 1 is filled with water and the wick holders on the bar 8 are adjusted in accordance with the spacing of the columns or coils of the radiator. The wicks, which may consist of strips of blotting paper or ordinary paper 15 toweling of the required width and length, are then inserted into the holders so that the lower ends are suspended in the water. The device is then placed with respect to the radiator, as indicated in Fig. 5, in which position 20 the plate 2 extends on the outside of the radiator and parallel thereto, and thus conceals the wicks and their holders. Due to the capillary attraction of the wicks water is drawn upwardly and is evaporated by the 25 heat of the radiator, whereby aqueous vapors fill the air and maintain a sufficient humidity of the air.

To render the removal of the device unnecessary, in order to permit inspection of 30 the level of the water in the receptacle 1, special indicating means is provided. The plate 2 is formed with an arcuate slot 13 and on its outside two graduation marks 14 are arranged at the slot, one of said marks 35 being labeled "Empty", while the other is designated by the word "Full". A lever 15 is pivotally secured at 16 to the plate, its upper end moving over said slot 13, while its lower end carries a float 17 which determines 40 the position of the lever in accordance with the water level. Preparatory to closing the device it is obvious that lever 15 must be turned about its pivot 16 so that its float 17 clears the pan.

Copies of this patent may be obtained for five cents each, by addressing the "Commissioner of Patents, Washington, D. C."

While I have indicated a humidifier by 45 way of example, it is understood that various alterations and modifications may be made within the skill of the expert, and I do not intend to confine myself to the exact details as shown in the drawing, but want 50 to avail myself of any such changes or departures which fairly fall within the scope of the invention, as pointed out in the appended claims.

I claim:

1. The combination with a radiator having a plurality of coils, a water receptacle adapted to be placed underneath said radiator, a cover hinged to said receptacle and adapted to be held in upright position so as 60 to extend parallel to said radiator, a bar extending parallel to said cover and fastened thereto, a plurality of holders slidably arranged on said bar, wicks secured in said holders and entering said receptacle, a float 65 operated means pivotally secured to said cover for indicating the level of the water in the receptacle, and means provided in said cover for determining the position of said float.

2. In combination with a heating radiator having a plurality of columns, a water receptacle arranged underneath said radiator, a cover hinged to said receptacle and adapted to be held in an upright position so as 75 to extend parallel to said radiator, means carried by said cover for drawing up water from said receptacle and evaporating the water, float operated means secured to said cover for indicating the level of the water 80 in said receptacle, and an arcuate slot in said cover to determine the position of said float operated means in accordance with the water level of said receptacle.

In testimony whereof I hereunto affix my 85 signature.

HORATIO GATES HOUGHTON.
